INFANT'S GARMENT

Nicholas G. Godshall, Ephrata, Pa., assignor to
 Walter W. Moyer Company, a partnership,
 Ephrata, Pa.

Application December 6, 1951, Serial No. 260,164

2 Claims. (Cl. 2—111)

1

The present invention relates to an infant's shirt-type garment of the type having tapes sewed to the interior thereof onto which diapers may be pinned; also, it relates to the method of tacking said tapes to the interior of the shirt, and to the necessary sewing machine attachments for carrying out the method.

It is well known in the art to provide an infant's shirt-type garment formed of knit material and having fabric loops or strips sewed to opposite sides of the center line of the front panel on the interior of the garment so as to constitute supporting means for attaching a diaper by safety pins. Such type of garment is shown in United States Patent 2,551,809 issued to Harry R. Ryan. An outstanding disadvantage of this construction of garment, such as shown in said Ryan patent, is that the ends of the loops or strips are generally cut in the form of a semicircle in order to correspond to the shape of a circular stitching used for attaching the strips or tabs to the interior of the garment. By such cutting of the strip ends in the form of a semicircle, there is a substantial waste of material from which the strips are cut. Additionally, I have found that contrary to the teachings of this patent, substantial improvement is obtained by attaching the strips to the garment by means of stitching extending along rectilinear paths instead of a non-rectilinear or circular path. Another outstanding disadvantage of the above well-known type of construction, such as shown in the patent, is that the conventional way of attaching the strips or tabs is by turning the shirt inside out and then sewing the tabs to the interior surface of the front panel of the garment, and thereafter turning the shirt right side out again. These turnings add substantially to the time required for constructing the garment, and thus increase manufacturing costs. Additionally, the above method results in stitching on the outside of the garment which is in the form of under stitching often referred to as "wrong side" stitching, since it has loose threads which must be trimmed and which stitching is not neat in appearance as the top stitching or so-called "right side" stitching which would occur, in this case, on the inner surface of the garment where it normally cannot be seen. Furthermore, in carrying out the conventional method of attaching tabs, as shown in the patent, whereby the garment is turned inside out, set in a sewing machine, and the tape or tab is placed on top thereof, and thereafter clamped by the conventional garment holding clamp, there is often a tendency for the garment to slip during

placement of the tape, thereby resulting in improper positioning of the tape.

An object of the present invention is to provide an infant's shirt-type garment wherein the interiorly stitched diaper-supporting tapes or strips are sewed in a manner that the right side stitching appears on the outside instead of the inside so as to considerably enhance the appearance of the garment when worn.

A further object of the invention is to provide a substantially triangular tacking for attaching the tapes to the interior of an infant's shirt-type garment which greatly increases resistance against stresses when the tapes are pulled and eliminates concentration of stresses on any one or more loops or strand sections of the knit fabric yarn.

A still further object of the present invention is to provide a novel attachment means for a flat bed type of sewing machine for enabling the sewing of tabs or tapes on the interior of infant garments without the necessity of turning the garment inside out or vice versa and which enables the right side stitching to be on the outside of the garment instead of the inside, thereby considerably improving the appearance of the outside stitching.

Other objects and advantages of the present invention will become apparent from a study of the following description taken with the accompanying drawings wherein:

Fig. 1 is a front view of an infant's shirt-type garment embodying the present invention;

Fig. 2 is an enlarged cross-sectional view taken along line II—II of Fig. 1;

Fig. 3 is a perspective view of a flat bed or long arm type of sewing machine including an attachment embodying the principles of the present invention for enabling the sewing of tapes along a triangular path and in the manner embodying the principles of the present invention;

Fig. 4 is an enlarged fragmentary side view of the arch clamp and associated parts shown in Fig. 3 and which are adapted to move in a horizontal plane along a triangular path with respect to the needle, and

Fig. 5 is an enlarged fragmentary top view of the feed plate and the respective clamps held thereagainst, all of which move in a horizontal plane along a triangular path during the stitching operation.

Referring more particularly to Figs. 1 and 2, numeral 1 denotes an infant's shirt-type garment formed of knit material, such as a tubular knit fabric of cotton, wool, rayon or mixtures

2

thereof. The garment is of conventional design and has sewed to the inside surface thereof strips or tapes 2 of woven fabric which are conventionally used for supporting diapers by attaching safety pins to the strips rather than to the shirt itself. Strips 2 are preferably made in the form of straight rectangular pieces of tape whose ends are cut along transverse straight lines so as to conserve strip material as compared to cutting strips with semicircular ends.

In accordance with the present invention, substantially increased strength of the stitching is provided by employing stitching 3 which extends along a triangular path, that is, along several rectilinear paths instead of along the conventional circular path. This enables the matching of the base of the triangle of the stitching with the end of the tape since both extend along straight transverse lines, and more important such triangular stitching eliminates the tendency of concentration of stresses along any one loop or strand section as often occurs when circular stitching is used.

An outstanding feature of the present invention resides in the method of fastening or so-called "triangular tacking" of the tapes of the interior of the garment in a manner so as to eliminate the necessity of turning the garment inside out and then, right side out, which is necessary according to the conventional method of stitching the tapes. The present invention relates to a method whereby the tapes may be attached or tacked to the inside of the garment without the necessity of turning the garment inside out and vice versa, therefore not only saving the operations of turning, but improving the appearance of the garment, inasmuch as the present method enables the right side stitching to be on the outside rather than on the inside as occurs in conventional constructions of infants' garments.

Fig. 3 shows a flat bed type of sewing machine such, as for example, a Singer Class 69 machine, with the conventional arch clamp 5 which is fastened to a feed plate 6. As is well-known in the art, the gearing of such machine is so arranged as to enable movement of the arch clamp 5 and feed plate 6 along a predetermined path, such as the conventional circular path, while the needle is reciprocating vertically along a fixed path. Thus, when the garment holding presser clamp 7 (which is vertically movable such as by means of the conventional treadle control, not shown) is lowered onto the garment so as to clamp it against feed plate 6, the presser clamp 7 together with feed plate 6 and arch clamp 5 all move along a circular path in a horizontal plane to provide circular stitching. In such conventional construction, clamp 7 has a circular hole instead of a triangular hole as shown.

In accordance with the present invention, the garment holding presser clamp 7 is provided with a triangular cutout instead of a circular cutout, and, of course, the machine must be constructed so that the feed plate 6 will move along a triangular path together with arch clamp 5 and a presser clamp 7. Presser clamp 7 is connected by means of supports 8 to the arch clamp 5 so that it will move together with the feed plate 6 in a horizontal plane along a triangular path while the sewing machine is reciprocating along a fixed, vertical path through the garment and tape which are clamped in place in the manner to be described.

According to the present invention, an additional attachment is provided in the form of a spring steel clamp 10 having ends 10a and 10b which are fastened to the arch clamp 5 by any suitable fastening means, such as bolts, screws, etc., and which clamp 10 at the other end thereof is provided with a V-shaped cutout terminating in end portions 10c which are preferably bent upwardly at the edges thereof to facilitate introduction of the tape or strip, such as 2, between the V-shaped legs of clamp 10 and the feed plate 6.

In operation, the tape, cut out in the shape of tape 2, is slipped underneath the spring clamp 10, immediately under the end thereof with the triangular cutout and terminating in end portions 10c. The clamp 10 is of spring steel or similar metal so as to afford a resilient clamping action on the tape sandwiched between it and feed plate 6. The lower portion of the garment is then slipped above spring clamp 10 and because of the elongated shape of clamp 10, enough of the garment is slipped over the length thereof until the part which is marked for matching with a corresponding marked portion of the tape, will come into registry with the latter in a given position within the triangular area defined by presser clamp 7. Thereafter, the presser clamp 7 is lowered such as by a treadle or other conventional control (not shown) so that it will clamp the garment (with its outside surface facing upwardly) onto the top of the V-shaped portion of the tape holding clamp 10. Then, the machine is operated so as to enable the feed plate 6, garment holding pressing clamp 7 and tape holding clamp 10 to move in unison in a horizontal plane along a triangular path while the needle is reciprocated along a fixed vertical path, thus resulting in stitching or tacking of the tape along a triangular path such as defined by the triangular cutout in the presser clamp 7. Upon completion of the triangular tacking, presser clamp 7 is raised and the garment is pulled out of its clamping engagement between clamp 10 and feed plate 6. Thus, the right side stitching will be on the outside of the garment, instead of on the inside as in conventional constructions, and there is eliminated any necessity of turning the garment inside out or vice versa, for the tape stitching operation.

Thus it will be seen that I have provided an improved infant's garment of the type having diaper supporting tapes tacked to the inside thereof, wherein the right side stitching appears on the outside of the garment so as to enhance its appearance, and wherein a triangular tacking is used instead of the conventional nonrectilinear or circular tacking, thereby considerably increasing the resistance to stresses in any one loop or strand section, and which allows the ends of the tapes to be cut along straight edges so as to conserve material as compared to cutting them along semi-circular paths resulting in waste of strip material; furthermore, I have provided a novel attachment for a flat bed and long arm type of sewing machine, particularly in the addition of a tape holding, spring clamp for making it possible to tack said tapes in the manner indicated without the necessity of turning the garment inside out and vice versa for the tacking operation, thereby reducing time normally required for the stitching or tacking operation as well as manufacturing costs.

While I have illustrated and described a certain specific embodiment of my invention, it will

be understood that this is by way of illustration, and that various changes and modifications may be made within the contemplation of my invention and within the scope of the following claims.

I claim:

1. An infant's shirt-type garment having a plurality of woven fabric tapes sewed to the inside surface thereof, each of said tapes being in the form of a single rectangular piece with straight ends extending crosswise of the garment and having the top end portion stitched to the inside surface of said garment by stitching extending along a triangular path with the base of the triangle extending in close, spaced parallel relationship with the top straight end of the tape, the "right side" or finished side of said stitching being on the outside of the garment and the "wrong side" or unfinished side of said stitching being on the inside of the garment.

2. The method of sewing a diaper-supporting tape on the inside surface of an infant's shirt-type garment, comprising clamping a panel por-

tion of said garment on top of said tape with the outside of said garment facing upwardly and underneath a sewing machine needle, then stitching an end portion of said tape by moving said clamped tape and garment in a horizontal plane along a closed triangular path while reciprocating the needle along a fixed vertical path, whereby stitching is provided with the "right side" thereof on the outside of the garment.

10 NICHOLAS G. GODSHALL.
